UNITED STATES PATENT OFFICE

COLVIN L. JOHNSON, OF ST. LOUIS, MISSOURI, ASSIGNOR TO JOHNSON AUTOMOBILE
LOCK CO., OF ST. LOUIS, MISSOURI, A CORPORATION OF MISSOURI

TRANSMISSION LOCK

Application filed January 31, 1927. Serial No. 164,889.

This invention relates to a transmission lock and particularly concerns itself with the provision of an improved locking mechanism which is associated with the gear shift lever and which may be conveniently locked and unlocked.

It is highly desirable that the key controlled portion of locking mechanisms of this type be conveniently accessible to the operator. 10 This result has heretofore been accomplished in certain instances by positioning the lock cylinder in the end of the lever or in the lever handle and connecting the same with the locking mechanism at the base or pivot point of 15 the lever by a suitable rod. Such constructions, however, have necessitated the use of undesirable bulky lever members or lever members of very expensive construction.

It is an important object, therefore, of the 20 present invention to provide an inexpensive and durable lever type transmission locking mechanism which is effective and convenient in operation and which at the same time obviates the need of a bulky lever member to 25 accommodate the locking mechanism and its connecting means.

Another important object of this invention resides in the provision of an improved mounting of the lever controlling means in 30 the shaft of the lever.

Other and further important objects of this invention will be apparent from the disclosures in the specification and the accompanying drawings.

35 The invention (in a preferred form) is illustrated in the drawings and hereinafter more fully described.

On the drawings:

Figure 1 is a side elevation with parts in 40 section showing an improved transmission lever lock embodying the principles of this invention.

Figure 1^a is an enlarged fragmentary detail section with parts in elevation taken 45 through the lever handle and showing the lock cylinder and attendant mechanism therein.

Figure 2 is a central vertical section with 50 parts in elevation taken through the pivotal mounting for the lever member.

Figure 3 is an enlarged section on the line III—III of Figure 1.

Figure 4 is an enlarged fragmentary section on the line IV—IV of Figure 1.

Figure 5 is a view looking along the line 55 V—V of Figure 1.

Figure 6 is a section on the line VI—VI of Figure 2.

Figure 7 is a section on the line VII—VII of Figure 2.

Figure 8 is an enlarged fragmentary detail with parts in section showing the locking sleeve in unlocked position.

Figure 9 is a view similar to Figure 8 showing the locking sleeve or collar in locked position.

As shown on the drawings:

The reference numeral 1 indicates a part of a gear shift housing cover in which a ball pivot member 2 is mounted for limited universal movement. Extending through the ball pivot member 2 and secured thereto by usual pin 3 is a lever member 4 which terminates in a ball handle portion 5. Mounted in an axial recess formed in the end of the 75 ball handle portion 5 is a lock cylinder 6 which may be rotated in the usual manner through a key 7. The key operated lock is of a conventional type wherein the key can only be removed when the rotary lock barrel 80 is in a given position. Although other means may be employed for securing the lock cylinder 6 in the end of the ball handle 5, I have found it desirable to secure a sleeve 8 to the end of the lever 4 by means of a blind set 85 screw 9 and suitable locking balls 10 and to mount the cylinder 6 in the upper end of said sleeve as clearly shown in Figure 1^a. The cylinder 6 terminates in a plug connection 11 which extends into a recess 12 in the upper 90 end of the lever 4 and is there connected with a wire or slender rod 13 which extends axially through the lever for a purpose to be described hereinafter. A passage or recess 95 through the lever through which said wire or rod 13 passes is formed by first milling a relatively deep groove in the lever and then welding a filling of metal such as shown at 14 in Figure 3 in the outer end of said groove. This leaves a longitudinal passage 100

through the lever in which the wire or rod 13 may be inserted. I have found that the outer end of the groove in the lever may be conveniently filled by first placing a pipe of wire 14^a therein and then completing the welding operation so that the wire and additional metal used in welding fill up the outer end of the groove flush with the surface of the lever. The exterior of the lever is then 10 properly smoothed and buffed at which time the exterior of the lever presents the same appearance as, and is for all practical purposes, a solid member.

Slidably mounted on the lever intermediate 15 the ends thereof is a casing 15 which is provided at its lower end with a flange 16 having a concavely recessed lower face 17 affording a cover for the rounded portion of the transmission housing cover 1 above the mounting 20 for the ball 2. Said casing 15 is normally urged resiliently upwardly by means of a ring or collar 18 which is slidably mounted on the lever member 4 and engages the underside of the flange 16 in the concave recess 25 17. Said collar 18 is in turn forced resiliently upwardly by a helical spring 19 which is engaged between the underside thereof and the upper face of the gasket 20 resting in the recess in the housing lever 1 above the ball 2. The gasket member 20 is preferably formed 30 of rubber composition or similar material designed to prevent vibration. In view of the fact that this gasket is of resilient material, I have found it desirable to provide additional means to prevent the lever being pulled 35 axially out of the housing cover and have therefore inserted an annular steel wire 21 in a groove in the housing cover directly above the ball 2. The lower end of the lever 4 is provided with a longitudinal groove 22 which 40 extends from a point within casing 15, as shown in Figure 4. Slidably mounted in this groove 22 is a wire rod or link 23 which is provided at its upper end with a lateral extension 23^a engaged in a notch 24 in the upper face of ring or collar 18. The lower end 45 of the rod or link 23 is also provided with a lateral extension 23^b which engages in an aperture in the locking collar or sleeve 25 slidably mounted on the lower end of the lever 50 4 and provided with integrally extending members 26 slidable on either side of the flattened end 4^a of said lever 4 (Figures 2 and 4).

It will be apparent from the construction 55 which has been heretofore described that when the casing 15 is pushed downwardly against the action of the spring 19 that the collar 18, rod 23 and collar 25 and locking projections 26 will be moved downwardly 60 therewith, whereupon the projections 26 will engage in notches formed in shifting blocks 27 of usual construction (see Figures 5, 8 and 9) to prevent lateral movement of the lever from neutral position to shift the transmission gears. Thus such movement of the cas-

ing in a downward direction will act to lock the lever 4 in neutral position.

It is, of course, necessary to provide means for locking the casing 15 in such downward position when it is desired to leave the vehicle 70 unattended in order that movement of the lever 4 from neutral position may be prevented. To accomplish this purpose, I have provided a lateral passage 28 in the lever 4 intermediate the ends of the casing 15 and in 75 this passage I have positioned a plurality of locking balls 29, the outer of which are adapted to engage in a rounded groove formed in the inner wall of the casing 15. These balls are adapted to be held outwardly in said 80 groove to retain the casing 15 in locked downward position by a rotatable locking pin 30 which is mounted in the lever on an axis intersecting the axis of the passage 28 and which is adapted to be rotated by the rod or 85 wire 13 when the lock cylinder 6 is rotated by virtue of the fact that said pin 30 is connected to the lower end of said rod or wire 13. The lower end of the pin 30 is flattened as shown at 30^a (Figure 2) so that it may be 90 turned at right angles to the position shown in Figure 2, whereupon the spring 19 will force the casing 15 upwardly past the balls 29, it being noted that the groove in the inner wall of said casing 15 is of such depth as 95 to receive less than half of the balls 29. In order to prevent longitudinal movement of the pin 30, the same is provided with a groove intermediate its ends into which projects the end of a pin 31 extending laterally into the 100 lever inside the casing 15. Upward movement of the casing 15 is limited by a suitable boss 32 secured to the exterior of the lever 4 and conveniently comprising a wire or similar member engaged in the groove of the 105 exterior thereof.

The lock cylinder 6 is so arranged that the key 7 may only be withdrawn therefrom when a torsional stress is exerted on the wire or rod 13, this torsional stress being transmitted by the flattened end 30^a of the pin 30 to resiliently force the balls 29 outwardly and insure their engagement in the groove in the inner wall of the casing 15 when said casing is forced downwardly to locked position.

In operating the devices it is not necessary to use the key to complete the locking operation since pushing down on the casing 15 until the groove in the inner wall thereof is in register with the balls 29 results in said 120 balls being automatically forced in the groove and the casing being locked in downward position and the lever is locked from movement in neutral position. When it is desired to unlock the lever, the key 7 is inserted in the cylinder 6 and the cylinder is turned so that the flattened end 30^a of the pin 30 is at right angles to the position shown in Figure 2 whereupon the spring 19 will automatically 125 force the casing 15 upwardly carrying the 130

5 collar 18, the rod 23 and the locking projections 26 therewith. The key may only be withdrawn when the cylinder is so positioned as to turn the flattened end 30^a of the pin 30 again to the position shown in Figure 2 at which time the balls are resiliently urged outwardly and snap into position in the groove in the casing 15 when the casing is pushed downwardly.

10 It will be apparent from the foregoing description that I have provided a lock mechanism which is of simple and durable construction and which may conveniently be unlocked. At the same time, due to the improved method which I have provided for mounting the rod or wire 13 in the lever 4, it is not necessary to use an undesirable large and bulky lever to accomplish the desired result and in view of this construction, the lever 15 may retain its neat appearance and at the same time embody the desirable feature of a locking control in the ball handle thereof.

20 I am aware that numerous details of construction may be varied through a wide range without departing from the principles of this invention, and I therefore do not purpose limiting the patent granted, otherwise than necessitated by the prior art.

I claim as my invention:

30 1. The combination with a gear shift lever, of an interiorly grooved casing slidably mounted thereon, locking means associated with said casing and operable thereby, a plurality of balls associated with the lever and adapted to be moved into the groove in the casing to lock the same from movement relative to the lever, and means for locking said balls in the last-mentioned position.

2. The combination with a gear shift lever, of an interiorly grooved casing slidably mounted thereon, locking means associated with said casing and movable thereby, a plurality of balls associated with the lever and adapted to be engaged in the groove in the casing to lock the same from movement relative to the lever, and means extending through the lever to the upper end thereof for locking said balls in the last-mentioned position.

3. The combination with a gear shift lever, of an interiorly recessed casing slidably mounted thereon, locking means associated with said casing and movable thereby, a plurality of balls associated with the lever and adapted to be engaged in the recesses in the casing to lock the same from movement relative to the lever, means for locking said balls in the last-mentioned position, and means for automatically moving the casing so that the recesses therein are above the balls when said last-mentioned means are unlocked.

4. The combination with a gear shift lever, of an interiorly grooved casing slidably mounted thereon, locking means associated

with said casing and operable thereby, a plurality of balls associated with the lever and adapted to automatically move into the groove in the casing when the same is in register therewith to lock the casing from movement relative to the lever. 70

5. The combination with a gear shift lever, of an interiorly grooved casing slidably mounted thereon, locking means associated with said casing and movable thereby, a plurality of balls associated with the lever and adapted to be engaged in the groove in the casing to lock the same from movement relative to the lever, and means for locking said balls in the last-mentioned position, the torsional strain on said last-mentioned means tending to force said balls outwardly when the casing is in unlocked position. 75

6. The combination with a gear shift lever, of an interiorly grooved casing slidably mounted thereon, a lever locking mechanism operable by said casing, a plurality of means loosely supported by the lever and adapted to engage the groove in the casing to lock the same from movement relative to the lever, 80 and means controlled from the end of the lever for locking said means in the last-mentioned position. 85

7. The combination with a gear shift lever, of an interiorly recessed casing slidably mounted thereon, a lever locking mechanism operable by said casing, a plurality of means loosely supported by the lever and adapted to engage the groove in the casing to lock the same from movement relative to the lever, 90 and a unitary means extending longitudinally through the lever for locking said means in the last-mentioned position and resiliently urging the same to assume such position when said casing is in unlocked position. 100

8. The combination with a lever, of a locking mechanism associated therewith, a longitudinal aperture in the lever, control means for the locking mechanism mounted in said aperture, and means welded in the outer end 110 of the aperture to prevent access to said control means.

9. The combination with a lever, of an auxiliary mechanism associated therewith, a longitudinal aperture in the lever, control means 115 for the auxiliary mechanism mounted in the bottom of said aperture, and means welded in the entrance to the aperture to prevent access to said control means.

10. The combination with a lever, of a locking mechanism associated therewith, a longitudinal aperture in the lever, control means for the locking mechanism mounted in the bottom of said aperture, and means permanently secured in the entrance to the aperture 125 to prevent access to said control means.

11. The combination with a lever, of a casing slidably mounted thereon, means carried by the lever for locking said casing from longitudinal movement relative to the lever, a 130

control means extending through the lever to the outer end thereof for operating said locking means, said control means exerting a resilient torsional stress on said first-mentioned means to force the same toward locking position.

12. In combination with an operating lever, a movable casing associated with an intermediate portion of said lever operable to lock said lever in a predetermined position, and lock means associated with an end of said lever for releasing said casing so as to permit of movement of said lever.

13. In combination with a gear shift lever, a movable element telescoped by an intermediate portion of said lever operable to lock said lever in a given position, and a lock connected to an end of said lever operable to release said element from its locked position so as to permit of movement of said lever.

14. In combination with a gear shift lever, lock means associated with an intermediate portion of said lever, lock means associated with an end of said lever, and means operatively connecting said two lock means, one of said lock means being operable to lock said lever in a given position and the other being operable to release said lever from its locked position.

15. In combination with an operating lever, a movable element associated with an intermediate portion of said lever adapted to be engaged by the operator's foot to lock said lever in a given position, and lock means associated with the upper end of said lever adapted to be actuated to release said movable element from said locked position so as to permit of movement of said lever.

16. In combination with an operating lever, a movable element associated with an intermediate portion of said lever adapted to be engaged by the operator's foot to lock said lever in a given position, a key operated lock associated with the upper end of said lever arranged to be actuated to release said movable element from said locked position so as to permit of movement of said lever, said lock being of the type wherein the key can only be removed when the lock is in a given position, and resilient means connecting said element to said lock means and being arranged so that when said lock is in said given position said lever is locked against operation.

In testimony whereof I have hereunto subscribed my name at St. Louis, Missouri.

COLVIN L. JOHNSON.
